UNITED STATES PATENT OFFICE.

JAN STEYNIS, OF BAY SHORE, NEW YORK, ASSIGNOR TO STEYNIS OZONE COMPANY,
A CORPORATION OF NEW YORK.

APPARATUS FOR STERILIZATION OF LIQUIDS BY OZONE.

1,228,712.

Specification of Letters Patent.

Patented June 5, 1917.

Application filed November 24, 1914. Serial No. 873,702.

To all whom it may concern:

Be it known that I, JAN STEYNIS, a subject of the Queen of the Netherlands, residing at Bay Shore, in the county of Suffolk, 5 State of New York, have invented certain new and useful Improvements in Apparatus for the Sterilization of Liquids by Ozone, of which the following is a full, clear, and complete disclosure.

10 This invention has for its object the improvement of apparatus for the sterilization by ozone of all liquids and principally of water.

These improvements relate to the apparatus in which the ozonized air is drawn into the mixing or sterilizing tank by the liquid to be sterilized and more particularly concern the arrangement of the injectors placed at the base of the mixing tank and the arrangement of safety devices interposed between the ozonizer and the injectors.

An apparatus comprising the improvements which form the subject of this invention is diagrammatically represented for 25 example in the annexed drawings.

Figure 1 is an elevation partly in section; Fig. 2 is a plan view, partly in section.

The mixing or sterilizing tank has at its upper end an overflow *b*. At the base of this 30 tank in a horizontal plane are arranged the nozzles *c*, *c*², *c*³, *c*⁴ of the injectors. These nozzles, which may be of any number, are arranged in the wall of the tank *a* and are disposed so as to direct the projected jet 35 tangentially to the wall of the tank in such a way as to give the liquid a rotating movement intended to insure an effective mixing of the particles of water and the globules of gas.

40 This construction is obviously superior to a construction in which the injecting device is located in the interior of the reservoir, thus interfering with the mixture of the liquid and gas.

45 The pipes *d* which feed the injectors are connected to the exhaust of the pump *e* which draws liquid through the pipe *f* from the reservoir *g*. This reservoir *g* is fed by any suitable method, preferably one which 50 insures a constant level of the liquid in the reservoir.

The ozonizer *h* is connected to the injectors by pipes *k* *k*', which are provided with valves *l* and *m* respectively. A safety reservoir *n* is interposed between each pipe *k*

and the corresponding pipe *k*' as shown. Each feed pipe *k*' is prolonged to the lower part of its reservoir *n* the bottom of which is provided with a valve *o* adapted to open an orifice of a larger diameter than that of the 60 pipe *k*'. This valve *o* is normally held upon its seat by the vacuum created in the reservoir *n* by the action of the injector.

If the reservoir *n* were omitted, and the pipes *k*, *k*' were connected directly together, 65 the vacuum maintained in these pipes by the action of the injector would draw the water back into the ozonizer *h* if, for any reason, the pump *e* should cease to operate. But with my improved arrangement, if the 70 pump ceases to operate, the vacuum will draw the liquid into the reservoir *n*. This will destroy the vacuum in this reservoir sufficiently to allow the valve *o* to open by gravity, and the liquid will flow off into a 75 suitable discharge pipe *p*. In this way the liquid is prevented from flowing into the ozonizer *h*.

My invention is not limited to the particular embodiment shown herein, but obviously many changes may be made in the structure shown, without departing from the spirit of the invention.

What I claim is:

1. In a device of the character described 85 a mixing tank, means for injecting liquid and gas into said tank, gas supplying means, a safety reservoir, a connection between said gas supplying means and said safety reservoir, and a connection between said safety 90 reservoir and said injecting means.

2. In a device of the character described a mixing tank, means for injecting liquid into said tank, gas supplying means, a safety reservoir, a valve in said reservoir, 95 a connection between said gas supplying means and said reservoir and a connection between said reservoir and said injecting means.

3. In a device of the character described, 100 a mixing tank, means for injecting liquid and gas into said tank, means for supplying liquid to said injecting means, gas supplying means connected to said injecting means, and a safety reservoir interposed in 105 the connections between the gas supplying means and the injecting means whereby the liquid is prevented from entering the gas supplying means in case of the failure of said liquid supplying means.

4. In a device of the character described, a mixing tank, means for injecting liquid and gas into said tank, said means being so constructed that the liquid and the gas in 5 the tank are given a rotary movement, gas supplying means, a safety reservoir, a connection between said gas supplying means and said safety reservoir, and a connection between said safety reservoir and said 10 injecting means.

5. In a device of the character described, a mixing tank, means for injecting liquid into said tank, said means being so constructed that the liquid in the tank is given 15 a rotary movement, gas supplying means, a safety reservoir, a valve in said reservoir, a connection between said gas supplying means and said reservoir, and a connection between said reservoir and said injecting 20 means.

6. In a device of the character described, a mixing tank, means for injecting liquid and gas into said tank, gas supplying means,

a safety reservoir provided with a valve 25 adapted to be held closed during the operation of the injecting means, and to be opened automatically when the injecting means ceases to operate.

7. In a device of the character described, a mixing tank, means for injecting liquid 30 into said tank, gas supplying means, a safety reservoir, a valve in said reservoir, a connection between said gas supplying means and said reservoir, and a connection between 35 said reservoir and said injecting means, adapted, during the operation of the injecting means, to exert a suction within said reservoir to hold said valve closed, and when the injecting means ceases to operate, to relieve the suction and permit said valve to 40 open.

JAN STEYNIS.
